UNITED STATES PATENT OFFICE.

PERCY A. BOECK, OF WORCESTER, MASSACHUSETTS, ASSIGNOR TO NORTON COMPANY, OF WORCESTER, MASSACHUSETTS, A CORPORATION OF MASSACHUSETTS.

ELECTRIC FURNACE.

1,158,971.

Specification of Letters Patent.

Patented Nov. 2, 1915.

Application filed November 2, 1911. Serial No. 658,091.

To all whom it may concern:

Be it known that I, PERCY A. BOECK, a citizen of the United States, residing at Worcester, in the county of Worcester and 5 State of Massachusetts, have invented certain new and useful Improvements in Electric Furnaces, of which the following is a specification.

This invention relates to electric furnaces, 10 the primary object of the invention being the provision of a furnace core or support for the resistance element, of a form and material adapted to afford a better distribution and more economical utilization of the 15 heat than heretofore.

My improved electric furnace core consists essentially of a cup-shaped vessel or receptacle formed of a very refractory material of high thermal conductivity, said vessel 20 having a helical groove on the exterior face of its sides or walls and a spiral groove in the lower face of its bottom, these grooves merging to form a continuous groove for the reception of the resistance wire or element.

An electric furnace core constructed in accordance with this invention is illustrated in the accompanying drawing wherein:

Figure 1 is a side elevation of the core; 30 Fig. 2 is a bottom view thereof; and Fig. 3 is a central vertical section of the core, showing also the resistance element, the covering therefor, and a crucible in position in the core.

In said drawings, 1 represents the furnace core or support for the resistance element, the core having, in the particular form illustrated, a cylindrical wall 2, having formed in its outer face a helical groove 3, in which is laid a resistance wire 4, which 40 may be of nickel-chromium alloy, platinum, or other suitable material. This wire is preferably formed, before being wound upon the core, into a continuous coil or helix, which is then wound in the grooves in the manner indicated in Fig. 3. This construction presents the particular advantages that the length of the resistor can be indefinitely increased, while at the same 45 time the liability of breakage is minimized. The bottom 5 is formed integral with the sides and provided with a spiral groove 6 on its lower surface, this groove 6 merging with the helical groove 3 as shown at 7, 55 Figs. 1 and 2.

The core, with the resistance element wound thereon, is covered with a thick layer of refractory cement, as shown at 8 in Fig. 3; and the whole is covered by a casing 9, which may be of iron. Between the refractory cement 8 and the casing 9 is a filling 10, preferably consisting of pounded magnesia, this filling constituting an electrical and thermal insulator. The ends of the resistance element 4 protrude in order that they 60 may be connected in the electric circuit, a convenient arrangement being as shown in Fig. 3, wherein the lower end of the wire extends directly downward from the center of the bottom of the core and through an 65 aperture 11 in the bottom of the casing 9. A crucible in position to be heated is shown at 12. In use the open end of the core is usually covered by any refractory and heat-retaining material.

The refractory cement or composition 8 which covers the resistance element 4 is preferably composed of previously molten alumina grains, and a relatively small proportion, say five to fifteen per cent. or somewhat more, of a suitable bond, as for example a plastic clay, or lime or magnesia. A composition of this character presents very important technical advantages for use in this connection: in particular it is chemically inactive with respect to the resistor and preserves the wire from corrosion; and by reason of its high thermal conductivity it conducts the heat rapidly from the resistor, thereby preventing overheating and consequent injury. At the same time it aids in the even distribution of heat throughout the core. Furthermore, by reason of the high specific heat of the cement it is adapted to serve as a heat accumulator or equalizer, preventing unduly large fluctuations of the interior temperature when the cover is removed or when articles are introduced into or removed from the furnace. It will be understood that a cement of this character may also be used in connection with any suitable core or support other than that herein described and claimed.

A furnace core constructed as herein described possesses several advantages: The distribution of the resistance element is such as to provide a substantially even temperature within the core, and the coils or turns of the resistance element are firmly held; at the same time the walls in contact with the

heating wire may be made very thin, which results in a better and more rapid conduction of heat.

A construction for a core of this character, in order to be free from danger of cracking during rapid changes of temperature, must be made of material which in addition to the necessary refractory character, possesses high thermal conductivity. Suitable materials for the purpose are previously molten alumina grains bonded by fritting together or by the use of a small proportion of a refractory ceramic bond; and silicid of carbon, bonded by recrystallization or otherwise. Such materials have a far higher thermal conductivity than porcelain or fire-clay, and are found to be durable and highly efficient.

I claim:—

- 20 1. An electric furnace comprising a receptacle having an open end, a helical groove formed in the outer surface of the body of said receptacle, and a spiral groove in its closed end, said grooves merging at the edge of the receptacle to form a continuous groove, a resistor within said groove and having its ends projecting respectively from opposite ends thereof, a refractory envelop of high thermal conductivity covering said resistor, and a heat-retaining packing surrounding said envelop.
- 25 3. An electric furnace comprising a receptacle having an open end, a helical groove formed in the outer surface of the body of said receptacle, and a spiral groove in its closed end, said grooves merging at the edge of the receptacle to form a continuous groove, a resistor within said groove and having its ends projecting respectively from opposite ends thereof, a refractory envelop covering said resistor and comprising previously molten alumina, and a heat-retaining packing surrounding said envelop.

40

tacle having an open end, a helical groove 30 formed in the outer surface of the body of said receptacle, and a spiral groove in its closed end, said grooves merging at the edge of the receptacle to form a continuous groove, a resistor within said groove and 35 having its ends projecting respectively from opposite ends thereof, a refractory envelop of high thermal conductivity covering said resistor, and a heat-retaining packing surrounding said envelop.

45

3. An electric furnace comprising a receptacle having an open end, a helical groove formed in the outer surface of the body of said receptacle, and a spiral groove in its closed end, said grooves merging at the edge of the receptacle to form a continuous groove, a resistor within said groove and having its ends projecting respectively from opposite ends thereof, a refractory envelop covering said resistor and comprising previously molten alumina, and a heat-retaining packing surrounding said envelop.

In testimony whereof, I affix my signature in presence of two witnesses.

PERCY A. BOECK.
